(57) **CLAIM**

The ornamental design for a display device, as shown and described.

DESCRIPTION

FIG. 1 is a perspective view of the display device.

FIG. 2 is a front view of the display device.

FIG. 3 is a rear view of the display device.

FIG. 4 is a left side view of the display device.

FIG. 5 is a right side view of the display device.

FIG. 6 is a top plan view of the display device.

FIG. 7 is a bottom plan view of the display device.

FIG. 8 is a perspective view of the display device of FIGS. 1-7 shown in an alternate state, showing a screen display.

FIG. 9 is another top plan view of the display device in an alternate state of use, showing information on a display area; and,

FIG. 10 is another bottom plan view of the display device in an alternate state of use, showing information on a display area.

The broken lines in the figures represent portions of the display device that form no part of the claimed design.

1 Claim, 6 Drawing Sheets
